US00D713135S

(12) **United States Design Patent**
Tucker et al.

(10) **Patent No.:** US D713,135 S
(45) **Date of Patent:** ** Sep. 16, 2014

(54) **SHOE SOLE**

(75) Inventors: **Scott Tucker**, Lafayette, CO (US);
Michael Thompson, Broomfield, CO
(US); **Darren Zrubek**, Boulder, CO
(US); **Keegan Rehfeldt**, Broomfield, CO
(US)

5,086,576 A 2/1992 Lamson
5,117,567 A 6/1992 Berger
5,154,682 A 10/1992 Kellerman
5,177,882 A 1/1993 Berger
5,179,791 A 1/1993 Lain

FIG. 1 is a bottom perspective view of the shoe sole showing
our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines comprise environmental structure and form
no part of the claimed design.

1 Claim, 6 Drawing Sheets
